AMUSEMENT RIDE CAR

Robert H. Gurr, 3206 Montana, Costa Mesa, Calif.

Filed June 29, 1961, Ser. No. 65,761

Term of patent 14 years

(Cl. D34—15)

FIG. 1

FIG. 2

FIG. 3

FIG. 4

FIGURE 1 is a three-quarter front top perspective view of an amusement ride car showing my new design;

FIGURE 2 is a top plan view of said car;

FIGURE 3 is a side elevational view of said car; and FIGURE 4 is a bottom view of said car.

I claim:

The ornamental design for an amusement ride car, substantially as shown.
